UNITED STATES PATENT OFFICE.

FRANKLIN G. NEUBERTH, OF ANSONIA, CONNECTICUT, ASSIGNOR TO THE S. O. & C. CO.,
OF ANSONIA, CONNECTICUT, A CORPORATION OF CONNECTICUT.

BUTTON.

1,210,677.

Specification of Letters Patent. Patented Jan. 2, 1917.

Application filed April 24, 1912. Serial No. 692,772.

To all whom it may concern:

Be it known that I, FRANKLIN G. NEUBERTH, a citizen of the United States, residing at Ansonia, in the county of New Haven and State of Connecticut, have invented certain Improvements in Buttons, of which the following description, in connection with the accompanying drawings, is a specification, like reference characters on the drawings indicating like parts in the several figures.

This invention relates to buttons of that class which comprise a rounded or dome-shaped head or body portion and a shank 15 by which the button may be secured in place.

It is an object of the invention to provide a novel button of this class comprising a metallic blank and a fast color covering, 20 that is to say, a covering of celluloid or other plastic material homogeneous in color. Such buttons possess great advantages in point of appearance and wearing qualities over those formerly known and may be produced in a great variety of colors to suit 25 widely different requirements. For example, buttons having a covering of white celluloid may be produced cheaply and used in place of the imported buttons now in demand for 30 white boots and shoes, or buttons having a covering of red or blue celluloid may be used with textile goods of similar color.

It has been found that a button comprising a two-part metallic blank presenting 35 a continuous upstanding flange and a curved portion partially separated from the flange by an annular recess or valley and having a coating of celluloid applied to its outer surfaces possesses the qualifications above 40 enumerated and also certain other advantages which will appear hereinafter.

As herein shown the metallic blank comprises a flanged disk and a dome-shaped member arranged to fit within the flange of 45 the disk portion, being retained in place by the engagement of the flange with its outer marginal edge.

A button of this character is well adapted to be manufactured cheaply upon a large 50 scale in that the parts of the metal blank may be assembled and handled accurately and rapidly by automatic machines. Moreover, the button itself is of strong construction, the body being formed by a convex 55 metal part which supports the covering

rigidly. The constructional feature which consists in arranging the flange of the base portion to surround and embrace the marginal edge of the convex portion is of importance and contributes largely to the strength of the button in that it positively prevents spreading of the convex portion when subjected to pressure upon its apex or crown. A further advantage incident to this construction results from the fact that 65 the annular recess formed between the inner surface of the flange and the outer surface of the convex portion affords secure and permanent anchorage for the plastic covering material. 70

While the metal portions of the button herein shown are primarily intended for use as a blank to be covered with plastic or other coating material, the metal blank may be finished in other ways if desired or it 75 may be used without coating.

The advantages above discussed and others incident to the invention will be best understood and appreciated from the following description of a preferred embodiment thereof selected for purposes of illustration and shown, on an enlarged scale, in the accompanying drawings, in which,— 80

Figures 1 to 3 represent the various steps 85 in assembling the metallic blank for the button; Fig. 4 is a view in perspective of a finished button, having a section broken away, and Fig. 5 is a view in perspective of a finished button in inverted position. 90

Referring to Figs. 1 to 3, it will be seen that the base of the metallic blank comprises a sheet metal disk 10 having its outer edge drawn or bent upwardly to form an annular flange 12. The disk 12 is provided at its center with an elongated slot 13 to receive the contracted portion of a shank 14 which comprises a loop, a contracted portion, and oppositely disposed feet which engage the inner face of the disk 10. 95

The body portion of the button is formed by a dome-shaped member 16 which rests at its lower edge upon the disk 10 within the flange 12. In making the button the member 16 is placed in position upon the disk 10 and then the flange 12 is bent inwardly to an extent sufficient to retain the member 16 in place. In this condition, therefore, the flange 12 overhangs the periphery of the convex or dome-shaped portion 16 and holds the latter in place. At its upper edge the 110

flange 12 is spaced slightly from the surface of the dome-shaped portion 16 with the result that there is formed a continuous recess or valley of substantially V-shaped cross section which extends about the button.

After the metallic portions of the button have been assembled the plastic covering 18 is applied and molded in place by the use of suitable dies in the manner well known to those skilled in the art. The covering material, in a plastic condition, is forced upon the upper part of the button and into intimate contact with the surface of the dome-shaped member 16 and the outer and upper surfaces of the flange 12. It is also forced into the V-shaped recess formed between the inner surface of the flange 12 and the outer surface of the dome-shaped member 16. It has been found in practice that this recess affords secure and permanent anchorage for the covering material.

The appearance of the under side of the button is well shown in Fig. 5 from which it will be seen that the smooth surface of the disk 10 imparts an attractive finish to this portion of the button and that the plastic covering 18, which may be of any desired color, completely covers all portions of the button which are conspicuous in use or subjected to wear.

Having thus described the button of my invention and briefly outlined one method of producing it, I claim as new and desire to secure by Letters Patent of the United States:

1. A button comprising a circular metallic base provided with an annular flange forming an acute angle with the base, a sheet metal body portion curved convexly at its margin and fitted into the angle between the base and the flange of the base, and plastic material covering the body portion and extending smoothly over the edge of said flange.

2. A button comprising a flanged disk, a shank set in the disk, a hollow metallic dome-shaped portion embraced at its edge by the flange of the disk, and plastic material covering the outer side of the flange of the disk and the surface of the dome-shaped portion.

3. A fast color button comprising a base

with an up-turned flange, a convex body portion seated within the flange and forming therewith a continuous circular recess substantially V-shaped in cross section, and plastic material covering the outer surfaces of the body portion and flange and filling said recess.

4. A fast color button comprising two metallic portions, one shaped to surround and fit upon the other, said portions flaring away from each other thereby forming a channel of V-shaped cross section, and plastic material filling said channel and covering the upper and outer surfaces of the metallic portions.

5. A fast color button comprising a metallic blank having a convex portion of sheet material and a bottom portion having a flange shaped to embrace the edge of said convex portion, said flange having its edge disposed toward the apex of the convex portion and shaped to retain said portion in place, and plastic material covering the convex portion and the edge of the flange.

6. A fast color button comprising a shank carrying disk having an upstanding rim, a convex sheet metal body portion held permanently in place upon the disk within the rim, and a plastic covering extending smoothly from the apex of the body portion over the edge of the rim of the shank carrying disk and about the outer surface thereof.

7. A fast color button comprising a hollow convex body portion with a circular margin, a separate narrow metallic band surrounding the margin of the convex portion, reinforcing it against expansion, the band being spaced from the surface of the convex portion at its upper edge to provide a recess, and plastic covering material molded over the outer surface and edge of the band and convex portion and filling the recess.

In testimony whereof I have signed my name to this specification in the presence of two subscribing witnesses.

FRANKLIN G. NEUBERTH.
